UNITED STATES PATENT OFFICE.

ROBERT M. BLACKMER, OF CONWAY, MICHIGAN, ASSIGNOR TO BLACKMER ROTARY PUMP, POWER AND MANUFACTURING COMPANY, OF PETOSKEY, MICHIGAN, A CORPORATION OF MICHIGAN.

ROTARY PUMP.

No. 869,050.

Specification of Letters Patent.

Patented Oct. 22, 1907.

Application filed October 13, 1905. Serial No. 282,617.

To all whom it may concern:

Be it known that I, ROBERT M. BLACKMER, a citizen of the United States, residing at Conway, in the county of Emmet and State of Michigan, have invented certain new and useful Improvements in Rotary Pumps, of which the following is a specification.

My invention relates to rotary pumps of the type employing a rotary piston or bucket-carrier and a series of radially movable buckets, and consists of certain features of improvement designed to increase the life of the pump and its separate parts, and its efficiency and reliability of operation, principally through the prevention of back-slip of the water past the working edges of the blades of the piston buckets.

My present improvements relate principally to a novel form of pump chamber and the relation of the piston buckets therein to the inlet and exhaust ports of said pump chamber; to a new and improved form of piston or bucket carrier designed to prevent interference with the movements of the buckets by the water and by foreign matter in the water; to improvements in the form of the bucket blade or scoop whereby the pressure of the water aids the centrifugal action in holding the working edge of the blade to the wall of the casing or chamber; and to other features that will herein-after appear.

A pump embodying my improvements is illustrated in the accompanying drawings, wherein,—

Figure 1 is a side elevation with one side plate removed and with the driving shaft in section; Fig. 2 is a perspective view of the piston or bucket carrier; Fig. 3 is a perspective view of one of the buckets; and Fig. 4 is a view in the nature of a diagram intended to illustrate the geometrical relations of the several parts of the pump chamber.

Referring to the drawings for a more particular description of the parts, 5 indicates as an entirety the casing, within which is a chamber closed in between parallel side walls and a curved cylinder wall within which the chamber is formed as parts or sectors of four cylindrical chambers. This circular wall is tapped on one side by the water inlet-port 6, the upper and lower boundaries of which at their junction with the inner curved wall of the casing are indicated at 7 and 8, respectively; and 9 designates the outlet or discharge-port, the similar boundaries of which are indicated at 10 and 11, respectively.

Referring to Fig. 4, for an illustration of the form and design of the pump chamber, A designates a center, from which, on a radius B, is struck an arc a—b, forming the upper portion of the curved wall of the casing. C is another center somewhat below and to one side of the center A, from which, on a radius D, is struck an

arc b—c. E is still another center, also located below and slightly to the other side of the center A, from which, on a radius F, is struck an arc d—a. Arcs b—c and d—a are substantially equal in extent and of the same curvature, and form the side portions of the curved wall of the casing. From the center A, on a radius G, is struck the arc c—d that forms the lower part of the curved wall of the casing. From the foregoing it will be seen that the space of the pump chamber is made up substantially of parts or sectors of four circles, two of which (the upper and lower (have a common center at A, but radii of different lengths; while the other two have radii of equal or substantially equal lengths but have separate centers C and E, respectively. The piston chamber may, therefore, be properly referred to as a triple-centered chamber. It will be observed that the upper edge 7 of the inlet-port is somewhat below or in advance of the point b of the cylinder wall, and the lower edge 8 of the inlet-port is likewise some distance below or in advance of the point c of the cylinder wall. It will also be observed that on the discharge side the upper edge 10 of the discharge-port is somewhat above or in advance of the point a of the cylinder wall, while its lower edge 11 is somewhat below or behind the point d of the cylinder wall. The terms "in advance of" and "behind", as above used, have reference to the direction of movement of the piston buckets.

Rotatably mounted in and transversely of the walls of the casing is a driven shaft 12, the axis of which coincides with the center A. Fast on this shaft, within the cylinder chamber, and in loose sliding contact with the side walls of the latter, is a piston or bucket-carrier, designated as an entirety by 13. This bucket-carrier is circular in peripheral contour, having a radius equal to the radius B of the upper and smaller sector of the pump chamber, whereby the periphery of said bucket carrier in passing over the arc a—b forms a sliding contact with the latter. The periphery of said bucket-carrier is cut away at intervals, forming pockets 14, which pockets are formed at one end with a semi-circular seat 15 adapted to receive the rounded fulcrumed end of a bucket, hereinafter referred to; there being also formed in the bucket-carrier a series of radial slots 16 that communicate with the opposite ends of the bucket pockets 14, respectively, and are curved on the arc of a circle struck from the center of the seat 15, the slots 16, like the pockets 14, extending from side to side of the bucket-carrier. In each side of the bucket-carrier is formed an annular groove 17 that is concentric with the axis of the carrier and communicates with the inner ends of the slots 16, so that the latter are in communication with each other through said annular grooves.

The buckets are each formed by a curved blade 18 of a form and size to slidably fit the slots 16, a pair of arms 19 connected to the outer portion of said blade on either side, and a rounded bearing-member 20 connecting the opposite ends of said arms and fitting the seat 15. The outer edge of each blade 18 that engages the inner curved walls of the pump cylinder is preferably beveled as shown at 21, so as to have a substantial line contact with the inner wall of the cylinder. Preferably, also, the back or convex side of the blade 18 is hollowed out or formed with one or more pockets 22, the purpose of which will appear in connection with the description of the operation.

In the operation of the pump the shaft 12 is rotated at a high speed in clockwise direction as shown in Fig. 1, which causes the free ends of the buckets to be thrown outwardly under centrifugal force, aided by gravity through the lower half of the chamber, into contact with the rounded walls of the latter, the first effect being to exhaust the air contained in the chamber, after which the water enters under atmospheric pressure and primes the pump. Thereupon, as soon as the outer or working edge of the blade of one of the buckets passes the point *b* (Fig. 4), it begins to move outwardly beyond the periphery of the piston or bucket-carrier, and as soon as it reaches the point *7* it begins to cut through the water entering through the inlet-port, sweeping the body of such water before it, and at the same time gradually moving outwardly from its seat. By the time the outer edge of the blade has reached the point *c*, the bucket is at practically the outer limit of its throw, and, as it passes the point *8*, it takes its full load and carries it on under substantially constant pressure to the lower edge 11 of the orifice of the discharge-port. As it sweeps over the extended area of the orifice of the discharge-port, the bucket is gradually forced back into its seat in the piston, the gradually contracting space bounded by the face of the latter, the bucket-blade and the plane of the orifice of said discharge-port serving to force the water out through the latter. By the time the blade has reached the point *a*, it is fully retracted within its seat; and therefore the bucket travels through the arc *a*—*b*, in fully retracted position, and with a small body of confined or "dead" water which is carried around bodily between the upper edge 10 of the discharge-port orifice and the point *b* of the wall of the pump, forming a water packing.

It will be observed that both ports of the pump casing extend to some distance within the lower sector of maximum radius of curvature, the arc of which is measured by the line *c*—*d* (Fig. 4). The object of this is that the bucket may be at its full or maximum throw before receiving and delivering its full load. As fast as each bucket passes over the discharge port, the full pressure is gradually thrown upon and received by the next following bucket, thus enabling the advance bucket to be readily forced to its seat as it approaches the upper and smaller arc of the casing. The purpose of extending the upper edge 10 of the discharge-port a short distance into the bucket-retracted arc *a*—*b* is to permit a limited continued discharge of the water after the bucket has entered upon the travel of said arc, which prevents the water from pocketing or jamming.

The form of bucket as shown in the drawings is such

that the inner part of the blade 18 is at all times in the slot or recess 16, never entirely leaving the latter. This prevents any hard or foreign substance that may be contained in the liquid from getting jammed between the blade of the bucket and its run-way and preventing the bucket from closing freely. The yoke-shaped form of the bucket allows the water to readily pass between the arms thereof into and out of the bucket seat as the bucket opens and closes, so that at all times there is a substantially equal fluid pressure on all parts of the bucket blade. The groove 17 connecting the inner ends of the slots or run-ways 16 constitutes a circular bypass for the water so that as one blade returns into its guide-slot, it forces the water out of the latter through the by-pass 17 and into the guide-slots of the other blades which are moving outwardly, thus assisting the outward throw of the latter. The portion (arc *a*—*b*) of the inner wall of the casing which is always in contact with the periphery of the piston or bucket-carrier is of greater length than the length over all of each bucket pocket, so that the openings in the piston formed by said pockets are fully covered between the discharge and inlet ports, and there is no opportunity for the water to pass from the former to the latter. The pump will, as soon as primed, carry a water packing, that is, the pockets, slots and grooves in the cylinder will always be filled with water; only the excess or that taken in under the piston and measured by the capacity of the space between the peripheral line of the piston and the inner peripheral line of the casing being discharged.

95

It will be observed that the buckets start on their outward throw before reaching the area of the inlet-port, and also that the full load is not thrown upon them until after they have attained the maximum of their outward throw. I find that this construction promotes the efficiency of the pump in the direction of preventing back throw of the buckets under full load and back slip of water past the outer operating edge of the bucket. The hollowing out of the back sides of the blades, as shown at 22 by creating a pocketed abutment directly across the path of the inflowing water, increases the effective pressure upon the blade from the inlet side of the pump as the blade takes up its full load, thus contributing to the prevention of back throw of the bucket, which, in pumps of this general type, has hitherto proved a serious fault.

100

In constructing the curved walls of the casing, the ends of the several different arcs should be joined on as nearly continuous lines as practicable, so that the bucket blades, in moving outwardly and inwardly, will travel evenly and smoothly, passing from one area to the next with a minimum of variation from a uniform swinging movement.

I claim:

1. In a rotary pump, a pump casing formed with parallel side walls and a cylindrical wall having arcs of different degrees of curvature, said casing having an inlet-port located some distance beyond one end of the arc of smallest radius, and a discharge-port on the opposite side of the cylindrical wall therefrom the orifice of which overlaps the other end of the arc of smallest radius, in combination with a rotary bucket-carrier mounted in said casing concentric with the arc of smallest radius, and a series of buckets mounted in pockets formed in the periphery of

120

125

said bucket-carrier and having radially swinging blades adapted to engage the inner surface of the cylindrical wall of the casing under centrifugal action, substantially as described.

- 5 2. In a rotary pump, a pump casing formed with parallel side walls and a cylindrical wall, the latter having top and bottom portions formed on arcs of greater and less degrees of curvature, respectively, and side portions formed on arcs of intermediate degrees of curvature, said 55 casing having inlet and discharge ports on opposite sides of its cylindrical wall, the lower margins of which overlap the ends of said arc of less curvature, in combination with a rotary bucket-carrier mounted in said casing concentric with the center of said arc of greater curvature, and a series of buckets mounted in pockets formed in the periphery of said bucket-carrier and having radially swinging blades adapted to engage the inner surface of the cylindrical wall of the casing under centrifugal action, substantially as described. 60
- 10 3. In a rotary pump, a pump casing formed with parallel side walls and a cylindrical wall, the latter having top and bottom portions formed on arcs of greater and less degrees of curvature, respectively, and side portions formed on arcs of intermediate degrees of curvature, said casing 65 having an inlet-port the upper edge of whose orifice is located some distance beyond one end of said arc of greater curvature while its lower end overlaps the arc of less curvature, and a discharge-port whose lower end overlaps the other end of said arc of less curvature while its upper end overlaps the other end of said arc of greater curvature, in combination with a rotary bucket-carrier mounted in said casing concentric with the center of said arc of greater curvature, and a series of buckets mounted in pockets formed in the periphery of said bucket-carrier and having 70 radially swinging blades adapted to engage the inner surface of the cylindrical wall of the casing under centrifugal action, substantially as described.
- 15 4. In a rotary pump, a pump casing formed with parallel side walls and an intermediate cylindrical wall having inlet and outlet ports on opposite sides thereof, in combination with a rotary bucket-carrier mounted in said casing eccentrically thereof, the periphery whereof is formed with pockets for the buckets and curved radial slots communicating with one end of said pockets, respectively, and a series of rocking buckets carried in said pockets and having curved blades reciprocably mounted in said slots, the outer edges whereof are adapted to engage the inner surface of the cylindrical wall of the casing under centrifugal action, substantially as described. 75
- 20 5. In a rotary pump, a pump casing formed with parallel side walls and an intermediate cylindrical wall having inlet and outlet ports on opposite sides thereof, in combination with a rotary bucket-carrier mounted in said casing eccentrically thereof, the periphery whereof is formed with bucket-receiving pockets, and a series of rocking buckets carried in said pockets and having radially swinging blades, the rear sides of which are recessed to augment the pressure effect of the water thereagainst and aid centrifugal action in maintaining the outer edges of said blades in sliding contact with the inner surface of the cylindrical wall of the casing during the travel of said 80 blades from the inlet to the discharge port, substantially as described.
- 25 6. In a rotary pump, a pump casing formed with parallel side walls and an intermediate cylindrical wall having inlet and outlet ports on opposite sides thereof, in combination with a rotary bucket-carrier mounted in said casing eccentrically thereof, the periphery whereof is formed with bucket-receiving pockets, and a series of rocking buckets carried in said pockets and having radially swinging blades, the rear sides of which are recessed to augment the pressure effect of the water thereagainst and aid centrifugal action in maintaining the outer edges of said blades in sliding contact with the inner surface of the cylindrical wall of the casing during the travel of said 85 blades from the inlet to the discharge port, substantially as described.
- 30 7. A piston-bucket for use in rotary pumps consisting of a blade, a bearing member, and one or more arms narrower throughout than the blade connecting the latter adjacent to its operating edge with said bearing member, substantially as described. 90
- 35 8. A piston-bucket for use in rotary pumps consisting of a blade having a beveled operating edge adapted to afford a substantially line contact with the wall of the pump cylinder, a bearing member, and one or more arms narrower throughout than the blade connecting the latter adjacent to its beveled edge with said bearing member, substantially as described.
- 40 9. A piston-bucket for use in rotary pumps having a blade formed with a recess on its rear side, substantially as and for the purpose described. 95
- 45 10. A piston-bucket for use in rotary pumps consisting of a blade having a beveled operating edge adapted to afford a substantially line contact with the wall of a pump cylinder and also having a recess on its rear side, a bearing member, and one or more arms connecting the latter with said bearing member, substantially as described.
